UNITED STATES PATENT OFFICE.

CHAUNCEY G. DIBBLE, OF FARMINGTON, IOWA, ASSIGNOR OF ONE-HALF
TO FREDERICK E. BANGS, OF NEW HAVEN, CONNECTICUT.

BRIDGE.

SPECIFICATION forming part of Letters Patent No. 293,427, dated February 12, 1884.

Application filed November 26, 1883. (No model.)

To all whom it may concern:

Be it known that I, CHAUNCEY G. DIBBLE, of Farmington, in the county of Van Buren, and State of Iowa, have invented a new Improvement in Bridges; and I do hereby declare the following, when taken in connection with the accompanying drawings and the letters of reference marked thereon, to be a full, clear, and exact description of the same, and which said drawings constitute part of this specification, and represent, in—

Figure 1, a side view; Fig. 2, an under side view, looking up; Fig. 3, a transverse section at the point where the suspension-rod connect with the chords, enlarged; Fig. 4, an enlarged perspective view, showing the connection between the suspension-rod and chords.

This invention relates to an improvement in the construction of that class of bridges in which an arched beam is arranged to support the platform, the horizontal thrust of the arch resisted by a horizontal tie extending from one end of the arch to the other on substantially the chord line, and commonly called "bow-string-bridge," the object of the invention being to connect the chord to the arch at intervals in such a manner that the chord itself aids in giving rigidity to the platform over and above that which it naturally gives when employed simply as a chord, and also to prevent possible transverse vibration of the bridge; and the invention consists in the construction, as hereinafter described, and more particularly recited in the claim.

35 A represents the arched beam, springing from a suitable block or abutment, B, at each end.

C are the cross-ties upon which the platform rests.

40 D is the chord running from end to end of the beam A, and is preferably made of a pair of cables. On this chord the ties C rest, and between the ties C and the beam A struts a are arranged to fix the distance between the ties and the beam. From the beam, and near the point where the struts bear, suspending-rod b extend down to a point, say, about flush with the top of the ties. These suspending-rod are bent into V shape, the bend of the V being at the bottom, and the two ends secured in the beam, as shown. Through the angle of the V the chord D takes a bearing, as at d. This is best done, as seen in Fig. 3, by plac-

ing a bar, e, transversely across upon the under side of the chords; this bar to rest in the bend d of the suspending-rod. The arrangement of the bearing-point between the suspending-rod and the chord nearly flush with the upper surface of the ties gives a bend to the chord, it passing over the bend in the suspending-rod, thence down beneath the tie, and up again to the bend in the next suspending-rod, as clearly seen in Fig. 1. This bending of the chord gives to it a brace-like effect, and great stability to the bridge.

45 To resist lateral vibration, I arrange beneath the platform curved tie-rods or cables E. These rods start from near the foot of each truss or beam, and curve inward to near the center of the bridge, thence returning to the foot at the other end. At each tie connection is made with the tie-rods E. These tie-rods thus arranged form arches to resist transverse strain or vibration, giving to the platform, transversely, substantially such a support as 50 the arched beam gives to the bridge vertically, and so that the bridge, when complete, is a solid structure, substantially as firm transversely as vertically. It cannot under any influence "sway" or attain any lateral vibration.

55 While I prefer to bend the rods b b at their point of connection with the chords, these rods may be made separately and arranged in the same diagonal position to the struts, the two 60 between each pair of struts brought substantially together midway between the ties, and connected with the chords at that point.

I claim—

65 The combination of the arched beams A, the transverse ties C, carrying the platform, vertical struts a between said ties and beam, chords D, extending from the foot of the arch at one end to the foot at the opposite end, and the diagonal suspension-rod b, extending from the arch near the struts to the chord intermediate between the ties, and there connected with the chord at a point above the plane of the bottom of the ties, whereby an upward bend is produced in the chords between the ties, substantially as described.

CHAUNCEY G. DIBBLE.
